Primary Examiner—Prabhakar Deshmukh*Assistant Examiner*—Derrick Holland(74) *Attorney, Agent, or Firm*—Lovells LLP(57) **CLAIM**

The ornamental design for a solar power generation assembly, as shown and described.

DESCRIPTION

FIG. 1 is a front and left side perspective view of a solar power generation assembly showing my new design;

FIG. 2 is a rear and left side perspective view thereof; and,

FIG. 3 is a top and front side perspective view thereof.

The broken lines shown represent unclaimed subject matter and form no part of the claimed design.

The broken lines immediately adjacent to the claimed areas in the views represent the boundaries of the design. None of the broken lines form any part of the claimed design.
